UNITED STATES PATENT OFFICE

JOHN FREDERICK SIMMANCE AND JACQUES ABADY, OF LONDON, ENGLAND.

GAS ANALYSIS APPARATUS.

No. 887,706.

Specification of Letters Patent.

Patented May 12, 1908.

Application filed April 22, 1907. Serial No. 369,640.

To all whom it may concern:

Be it known that we, JOHN FREDERICK SIMMANCE, engineer, and JACQUES ABADY, barrister-at-law, subjects of the King of Great Britain, and residents, respectively, of 17 Ravenscourt Park, Chiswick, London, S. W., England, and Fountain Court, Temple, London, E. C., England, have invented certain new and useful Improvements in Gas Analysis Apparatus, of which the following is a specification.

A common method of examining a gas or gaseous mixture for the detection and estimation of certain constituents is to measure off a definite quantity, expose the same to the action of a suitable reagent, and re-measure, the difference between the volumes of the gas or gaseous mixture before and after the reaction affording a guide to the estimation (quantitative or qualitative or both) of the constituent or constituents sought. To carry out this operation with the usual apparatus demands some skill, and it is the object of the present invention to provide an improved method of and apparatus for performing the operation such that, notwithstanding an increase in the accuracy of the result obtained, little or no skill will be required in the operator.

According to the present invention the gas or gaseous mixture to be tested (whatever the pressure at which it reaches the apparatus) is always and automatically brought to the same pressure, so that a series of volumetric tests, if performed under identical conditions as regards temperature, will yield results having a uniform degree of accuracy and value.

In the accompanying drawings, which are designed to illustrate the invention in an elementary or diagrammatic manner, Figure 1 shows a rudimentary form of the improved apparatus; Fig. 2 shows the same apparatus in combination with means whereby the rise and fall of the first bell is brought about automatically so as to cause the gas which is to be tested to be inhaled by the bell. Fig. 3 shows a detail of a modification; and Fig. 4 shows a form of the apparatus wherein the expansible chambers are constituted by cylinders in which pistons are fitted to reciprocate.

Similar letters of reference indicate corresponding parts throughout the drawings.

Referring to Fig. 1, the expansible chambers A and B are the bells of two gas-holders,

each of (say) about 500 cubic centimeters capacity, A being however slightly larger and heavier than B. The respective bells, which are immersed in liquid seals contained in tanks A and B, are connected together in series whereof A is the first, tubes a and b which enter the bells through the bottom of the respective tanks and serve alternately as inlets and outlets for the corresponding bells, b being for this purpose branched upon a gas supply pipe C which leads from a small hand pump as at D, supplying the gas or gaseous mixture to be tested and discharged as at d to waste. The gas supply to the respective holders is controlled by three taps on the pipe C, the first tap c being between the pump D and the branch a leading to the first and larger bell A, the second c between the branches a and b, and the third c being between the branch b, leading to the second and smaller bell B, and the waste outlet d. The bells A and B are approximately counterbalanced by means of weights E and F attached to cords passing over pulleys e and f respectively.

A vent pipe G communicating with the interior of the bell A is attached rigidly to the latter, preferably at a point in the crown, and is downwardly bent so as to be adapted to be sealed in an independent vessel G¹ containing a suitable liquid, such for example as glycerin. The pipe G is of less length than the bell A, so that when the bell A stands at about its highest level the mouth of the pipe G may be unsealed.

Attached to (or operated by) the bell B is a pointer h which is adapted to work over a scale H divided into 100 equal parts, for indicating the amount of gas not absorbed, the zero and highest points of the scale being indicated by the pointer when the bell is near the lowest and highest points of its vertical movement respectively. Whereas the liquid or liquids in A¹ and G¹ should be inert relatively to the gas, or ingredients of the gaseous mixture to be tested, the liquid in B¹ may be a solution of the reagent employed in making the test. A convenient means of insuring intimate contact between said reagent and the gas entering the bell B is (see Fig. 2) a tube b¹ of metal gauze attached at top to the bell B and adapted to work freely over the pipe b, the tube b¹ being of approximately the same length as the bell, so that each time the bell rises in consequence of gas entering it through the pipe b, a film of the re-

agent will be carried up by and spread over the guaze tube b^1 , through whose meshes the gas as it enters is compelled to pass.

Instead of the reagent being contained in a solution constituting the liquid seal in the tank B^1 , it might be in the form of a solution contained in a wash-bottle or equivalent apparatus situated in the course of the pipe C between the tap c^1 and the pipe b , as indicated at I in Fig. 1, so that the gas before passing into the bell B will be compelled to bubble through the reagent. In this case the bell B would contain a liquid which is inert relatively to the gas or to the constituents of the gaseous mixture to be tested.

With the apparatus as described the testing operation is performed as follows:—The tap c^1 separating the bells A and B having been closed, and c^1 opened, the gas or gaseous mixture to be tested is forced by the pump D into the bell A until the latter rises so far as to lift the vent-pipe G high enough in the vessel G^1 to permit a portion of the gas to bubble through the sealing liquid therein, the bell A however always remaining sealed in the tank A^1 . While the gas is still bubbling through the sealing liquid in G^1 , the tap c^1 is closed and the pump D stopped, whereupon the bell A sinks by its own weight, driving the vent-pipe G lower in its vessel G^1 until the escape of gas through this pipe ceases, when the bell will remain stationary. Obviously this condition of equilibrium will be reached when the depth of the seal corresponds to the weight of the bell, and inasmuch as this weight is constant, the position of the bell at which equilibrium is attained will also be constant, and the bell will therefore always measure off an equal quantity of gas, whose volume may be determined by adjusting the level of the liquid in the vessel G^1 . The tap c^1 being thus closed, as is also the tap c^2 , the tap c^2 separating the bells A and B is now opened, with the result that the bell B which is lighter than A , will be charged with gas from A as the latter descends, the reagent in the tank B^1 or wash-bottle I meanwhile absorbing any constituent or constituents of the gas or gaseous mixture, so that the volume which enters the bell B will be correspondingly less than that which is expelled from the bell A . The difference will be expressed upon the scale H as a percentage of the volume originally contained in the bell A , this scale having been previously so graduated and adjusted that a rise of the pointer h from zero to 100 on the scale will correspond exactly with a full and unaltered volume of gas in the bell A . Hence the indication made by the pointer h will always show, directly, the precise proportion of the gas or gaseous mixture not absorbed by the reagent. In order to empty the bell B , the tap c^2 is shut and c^1 is opened so as to allow the bell B to descend and expel its gaseous

contents to waste. At the same time the tap c^1 may be reopened to admit a fresh supply of gas to the bell A (see Fig. 1).

The requisite preliminary adjustment of the scale H may be readily effected by correspondingly adjusting the height of the surface level of the liquid seal in the vessel G^1 , air or some gas not liable to be effected by the reagent being employed for the purpose. If however the only gas available for determining the adjustment be drawn from the same source as that which is to be tested, the special impurity (whose quantity is to be subsequently estimated by the test) must be removed before the gas is allowed to enter the bell A . In any case the level of the liquid seal in the vessel G^1 must be made such that the descent of the bell A (corrected by the bubbling out of the surplus gas through the seal in G^1 as before described) will cause the bell B to rise exactly from zero to 100 on the scale H . The level of the liquid seal in G^1 , thus determined, should be carefully marked and adhered to, so that when a gas or gaseous mixture which is effected by the reagent is subsequently passed from A to B , the resulting reduction in its volume will, as indicated by the scale H , be an actual percentage of the original quantity.

The force pump D , instead of being worked by hand, might be actuated by mechanical power adapted to operate continuously especially in cases where it is desired to carry out a practically continuous series of tests concurrently with the progress of some other operation or manufacture. Thus for example the pump might be driven by gearing operated by a weight or weights, clockwork, water power, an electric motor, or (particularly where it is required to ascertain the constituents of the flue gases from a furnace) by chimney draft, or by any combination of different forms of mechanical power. In such cases the taps c^1 c^2 c^3 or their equivalents would require to be operated or controlled by the power employed to actuate the pump. Instead, however, of using a force pump to inject gas into the bell A , the latter might itself be made to serve as a suction pump, a convenient arrangement for this purpose being illustrated in Fig. 2 in combination with devices whereby the action of the apparatus is rendered entirely automatic. For the weight E , Fig. 1, whereby the bell A is approximately counterbalanced, is substituted a float J adapted to rise and fall within an open-topped vessel J^1 , the weight of the float when unsupported by liquid in the vessel J^1 , being sufficient to raise the bell A so as to cause the latter to inhale a charge of gas through the pipe a . A stream of water is allowed to trickle constantly into the vessel J^1 through a pipe controlled by a tap j , while j^1 is a siphon tube connected with said vessel and adapted to

rapidly empty the same on the water therein rising somewhat higher than is required to raise the float J so far as to allow of the bell A descending to the full extent of its adjusted travel. The tap at c^1 and c^2 (Fig. 1) are replaced respectively by automatically acting non-return suction and delivery valves as indicated, while the tap c^3 which is normally held closed by means of a weight K attached to one arm of a lever k fast on the spindle of the tap-plug, is adapted to be opened temporarily by the weight K being overcome by that of the water discharged by the siphon tube j^1 into a cup K' mounted on the other arm of the lever k. The cup K has a perforated bottom or is otherwise adapted to allow of the water, which is periodically delivered into it, escaping after the tap c^3 has been opened by the reversal of the lever as indicated in Fig. 2.

The action of this apparatus is as follows:—On the vessel J¹ being emptied, the float J, ceasing to be supported, will descend and by so doing will draw up the bell A, the vacuum thus created in the latter being filled by gas drawn into the bell through the valve c^1 . The rate of flow of water through the tap j is so adjusted that as soon as the bell A attains the highest point in its travel the float J will commence to rise and will thereafter continue to ascend until the bell A has descended to the full extent of its adjusted travel. The bell A, by its descent, will expel its gaseous contents through the valve c^2 and pipe b into the bell B, the exit from which latter will meanwhile have been closed by the action of the weight K on the tap c^2 . The gas as it passes to the bell B will be acted upon by the reagent, and this bell will therefore rise to a height (as indicated by the pointer h on the scale H) corresponding to the amount of absorption produced by the action of the reagent. After the bells A and B have completed their downward and upward travels respectively, the water in the vessel J¹ will rise to the summit of the siphon tube j^1 , and the siphon coming into operation, the water in J¹ will be rapidly discharged and, by temporarily weighting the cup K', will cause the tap c^3 to be opened, and so held, long enough to allow of the bell B (which in this arrangement is made heavier than its approximate counterweight f) descending and expelling its gaseous contents to waste through the tap c^2 . The emptying of the vessel J¹ will meanwhile, as first explained have permitted the float J to descend, the entire cycle of operations thereupon commencing and being repeated as above described so long as water continues to flow into the vessel J¹.

It is to be observed that although the methods of working described with reference to the arrangements illustrated in Fig. 1 and Fig. 2 respectively, are identical both essen-

tially and as regards the results obtained, they differ with respect to the conditions existing in the bell A during part of the operation. In other words, while in both cases the gas in bell A, before being allowed to pass from A to B, is always brought to the predetermined pressure (usually, approximately atmospheric pressure) at which the test is to be actually made, the test pressure is arrived at from (so to speak) opposite sides in the two cases. Thus, in the case of Fig. 1 (where the gas is injected into A under a pressure above that of the atmosphere) the test pressure is reached by reducing the pressure originally existing in the bell A, whereas in the case of Fig. 2 (where the gas is drawn into A at a pressure below that of the atmosphere) the test pressure is arrived at by increasing the pressure originally existing in the bell A.

Now, under the conditions found in the arrangement shown in Fig. 1, it is obvious that the necessary reduction in the pressure of the gas in the bell A is effected by the escape of a portion of the gas through the vent-pipe G on the bell rising above a certain level, as already described. Under the conditions found in the arrangement shown in Fig. 2 however, the necessary increase in the pressure within the bell A results from the fact of the partial vacuum, created by the rise of the bell, becoming filled by the indraft of gas sucked into the bell. In both cases the pressure obtained within the bell A is determined by the depth of the liquid seal above the mouth of the vent-pipe G, and it will be evident that in order to conduct the test under actual atmospheric pressure, the bell A must be raised until the vent-pipe G is lifted, momentarily clear of its seal. This cannot result, however, in the entry of the air into the bell by way of the pipe G in either case. In the case of Fig. 1 the higher pressure within the bell will begin to escape through G before this pipe is lifted clear of its seal, and the moment equilibrium between the pressures inside and outside of the bell is attained (i. e. immediately after the supply of gas is cut off by the closure of the tap c^1), the bell will descend of its own accord and the tube G will become re-sealed.

In the case of Fig. 2, the partial vacuum created within the bell A as the latter is lifted, may be filled with gas as quickly as it is formed, but whether this be the fact or not, the ingress of air by way of the vent-pipe G, during such portion of the rise of the bell, as takes place after the exposure of the mouth of the vent-pipe will be prevented by the closure of the mouth of the pipe by a plug g of Fig. 2 of the liquid (e. g. glycerin) constituting the seal. This plug g, which will be carried up along with the pipe G by atmospheric pressure, will remain in the pipe until the bell begins to descend, whereupon the

pressure within the bell will increase to a degree even slightly above that of the atmosphere. It will be evident that during such increase in the internal pressure, no air can enter the bell by the pipe G, the period of equilibrium between the internal and external pressures (during which air might enter by diffusion owing to the liquid plug g then falling from the pipe), being of momentary duration. In order to insure a uniform volume of gas being obtained in the bell A, the stroke of the latter must be of sufficient length to admit of the reversal of the condition (as regards pressures respectively inside and outside of the bell, as just described) taking place before the pipe G has descended so deeply in its seal as to prevent the escape of any surplus gas from within the bell. In connection with this, it is to be noted that in the arrangement illustrated in Fig. 2, it is the weight of the bell B which determines the point at which the sealing of the vent-tube G of the bell A occurs. In order to insure accuracy, a very slow descent of the bell A is required, this being easily effected by a corresponding adjustment of the rate at which water is allowed to enter the vessel J through the tap j. In the event of the gas to be tested being already under pressure (as in the case of ordinary town's gas), it will be obvious that no outside power would be required to work the apparatus, excepting that if the apparatus be constructed substantially as described with reference to Fig. 1, the taps c¹ c² and c³ would require to be operated by hand. An automatically acting arrangement of valves has been already described with reference to the construction illustrated in Fig. 2.

In Fig. 3 is shown a mechanical arrangement which may be substituted for the liquid seal of the vent-pipe G. In this arrangement L is a rotary valve or plug-cock on the vent-pipe G near its mouth, the cock being normally held closed by a weighted lever l fast on the plug spindle, and being opened, at the required moment in the rise of the bell A, by the opposite end of the lever l encountering a stationary stop l'. In order to obviate all risk of ingress of air into the bell, a ball valve m closing inwardly, may be provided at or near the inner end of the vent-pipe G.

Fig. 4 illustrates a form of apparatus wherein the bells A and B constituting the expansible chambers, are replaced by open-topped vertical cylinders A² and B² wherein pistons A² and B² are fitted to work respectively. The piston A² is continually reciprocated by mechanical power, for which purpose it is attached to a piston rod a² connected to one end of a sway-bar Q fulcrumed at q and caused to rock in a vertical plane by means of a coupling rod q' attached to a me-

chanically revolved crank Q' and to a point 6: in the bar Q. The reciprocations of the piston A² cause the gas, which is to be tested, to be alternately inhaled into the cylinder A² and expelled therefrom into the cylinder B² beneath the piston B². On its passage between the cylinders, the gas is subjected to the action of the necessary reagent in a wash-bottle I, the rise of the piston B² being consequently less than would otherwise have been the case, by an amount corresponding to the absorption which has taken place in the wash-bottle I. This amount is shown upon a scale II by a pointer h moving as one with the piston B². The piston B² need not be attached directly to any rod coupled to the sway-bar Q, but after each upward stroke may be returned to its initial or lowest position by means of a vertically moving striker-rod b² reciprocated by the bar Q as indicated. The pressure obtained within the cylinder A² is determined by means of a valve-controlled vent-pipe G, provided with a mechanically operated rotary valve L and inwardly closing ball valve m as already described with reference to Fig. 3, the inner limb of the pipe G passing from above through the piston A².

The passage of the gas into and out of the respective cylinders A² B² is controlled automatically by a mechanically operated rotary valve or five-way plug cock C¹ shown diagrammatically in Fig. 4. At the commencement of each cycle of operations, the valve-plug is held by means of the weighted arm R (fast on its spindle r) in position to admit the gas from the supply pipe C to the cylinder A² by way of a pipe a², and at the same time to allow of the contents of the cylinder B² being discharged to the waste pipe d by way of a pipe b². On the piston A² attaining the highest point in its stroke, the valve-plug is rotated (by means of a cam R' operating upon an arm r' also fast on the spindle r) to a position wherein it permits the gas in A², and which is expelled therefrom by the ensuing descent of the piston A², to pass by way of the pipe a² and the wash-bottle I into the pipe b² and thence into the cylinder B², communication between the pipe b² and the waste outlet d being meanwhile cut off.

We claim—

- An apparatus for gas analysis comprising a liquid seal, a bell fitted to rise and fall in the liquid seal and connected with the source of the gas mixture to be analyzed, a venting device constituted by a liquid seal and an open tube connected at one end to the top of the bell, the other end of the tube being adapted to dip into the liquid seal, a second liquid seal, a second bell fitted to rise and fall in the second liquid seal, connected on the one hand to the first bell and provided with a waste outlet; and means for subjecting the gas mixture to the action of

an absorbent reagent during its passage from the first to the second bell, substantially as set forth.

2. In apparatus for gas analysis comprising a first expandible chamber connected with the source of the gas mixture to be analyzed, a second expandible chamber connected to the first expandible chamber and provided with a waste outlet, and means for subjecting the gas mixture to the action of an absorbent reagent during its passage from the first to the second chamber; a venting tube for the first chamber connected with the movable part of the said chamber and extending externally thereof, means for normally closing this tube, and means for automatically opening the tube to the atmosphere at a predetermined position of the movable part of the first chamber, substantially as set forth.

3. An apparatus for gas analysis comprising a first liquid seal, a bell fitted to rise and fall in the first liquid seal and connected with the source of the gas mixture to be analyzed; a venting device constituted by a second liquid seal and an open tube connected at one end to the top of the bell, the other end of the tube being adapted to dip into the second liquid seal; a third liquid seal, a second bell fitted to rise and fall in the third liquid seal, connected on the one hand to the first bell and provided with a waste outlet; and means for subjecting the gas mixture to the action of an absorbent reagent during its passage from the first to the second bell, substantially as set forth.

4. An apparatus for gas analysis comprising a first liquid seal, a bell fitted to rise and fall in the first liquid seal and connected with the source of the gas mixture to be analyzed; a venting device constituted by a second liquid seal and an open tube connected at

one end to the top of the bell, the other end of the tube being adapted to dip into the second liquid seal; a third liquid seal, a second bell fitted to rise and fall in the third liquid seal, connected on the one hand to the first bell and provided with a waste outlet; a mechanically actuated pump for effecting the introduction into the first expandible chamber of a charge of the gas to be analyzed; and means for subjecting the gas mixture to the action of an absorbent reagent during its passage from the first to the second bell, substantially as set forth.

5. An apparatus for gas analysis comprising a first liquid seal, a bell fitted to rise and fall in the first liquid seal and connected with the source of the gas mixture to be analyzed, a venting device constituted by a second liquid seal and an open tube connected at one end to the top of the bell, the other end of the tube being adapted to dip into the second liquid seal; a third liquid seal, a second bell fitted to rise and fall in the third liquid seal connected on the one hand to the first bell and provided with a waste outlet; means for causing said chamber to expand and contract automatically so as to alternately draw in and expel a charge of gas comprising a vessel fed by a constant supply of liquid, a siphon for periodically emptying the vessel of the liquid, and a float connected to the chamber and adapted to be raised or lowered by the liquid in the vessel; and means for subjecting the gas mixture to the action of an absorbent reagent during its passage from the first to the second bell, substantially as set forth.
